UNITED STATES PATENT OFFICE.

HARRY HUGH WOLFE, OF KILBURN, LONDON, ENGLAND, ASSIGNOR TO ERNEST FREDERICK BAILEY, OF LONDON, ENGLAND.

DEVELOPING RECEPTACLE FOR AUTOMATIC PHOTOGRAPHIC MACHINES.

Application filed January 4, 1923. Serial No. 610,674.

To all whom it may concern:

Be it known that I, HARRY HUGH WOLFE, a subject of the King of Great Britain, residing at 26 Brondesbury Villas, Kilburn, in the county of London, England, have invented new and useful Improvements in Developing Receptacles for Automatic Photographic Machines, of which the following is a specification.

- 10 The invention relates to a developing receptacle which is used in an automatic photographic machine and into which a sensitized support is delivered and developed.
- 15 Such an automatic photographic machine is shown and described in the specifications of Wolff's British Patent No. 18699, dated August 13th, 1909, and Wolff's British Patent No. 6370, of 1912, dated March 15th, 20 1911, under international convention, but in that machine there were four developing receptacles. In the first of these receptacles a photographic plate was developed and in the second the plate was fixed. The plate 25 was then transferred to a copying apparatus where a card was exposed to the influence of light passing through the negative. The card then entered the third receptacle in which it was toned and fixed and finally 30 it entered the fourth receptacle where it was washed.
- The object of the present invention is to provide an improved developing receptacle in which a sensitized card which has been 35 exposed to light coming through a lens may first be developed, then rinsed with acidulated water, then treated with potassium permanganate slightly acid, then treated with sodium sulphite, again treated with a 40 developer and simultaneously submitted to the action of electric light, which transforms the silver bromide remaining in the card into a positive, then washed with acetic acid, then fixed, then washed and finally 45 treated with formaldehyde.

The receptacle is as usual narrow in cross section to receive the card in its frame and is closed at its lower end by a removable stopper which when removed allows the card 50 to drop out of the receptacle to be dried and delivered.

According to the present invention the receptacle is provided at its sides near the upper part thereof with several inlets 55 through which the various solutions or water

may enter the receptacle. The receptacle is also provided with an overflow pipe at its upper end and with an outlet at its lower end which is fitted with a valve. One side of the receptacle is provided with a transparent window and with a light tight funnel containing a source of light.

As the means for admitting liquid to such a receptacle the means for allowing a card to enter and to leave such a receptacle and 60 electrical means for performing various operations in regular order by means of electromagnets are well known and described in the British specifications above referred to, it is not considered necessary to show 65 and describe such apparatus in the present specification.

The invention is illustrated in the accompanying drawings in which Figure 1 is a front elevation of the receptacle and Figure 2 is a plan of the same. Figure 3 is a side elevation of the receptacle also showing the funnel. Figure 4 is a vertical section on the line 4-4 of Figure 1 showing also the means for opening the lower end 70 of the receptacle to allow a card to drop out of the same, the light tight funnel and the source of light.

a is the body of the receptacle which has a flared upper end at *a*¹ and opening *a*² 75 across its lower end. The opening *a*² is closed by a rubber cushion in the form of a tube *b* carried by a lever *b*¹ operated by known means.

The front of the receptacle *a* has an opening *a*³ fitted liquid tight with a transparent sheet *a*⁴ which may be made of glass or crystal. To the front of the receptacle *a* is fixed a plate *c* having a socket *c*¹ into which is fitted the light tight funnel *d*. The 80 plate *c* has strengthening ribs *c*² and the socket *c*¹ has lugs *c*³ by which the funnel *d* may be fastened to the receptacle *a* by screws *c*⁴.

The upper part of the receptacle *a* is formed 85 with several inlet tubes *e* *e*¹ *e*² through which different solutions and water pass into the receptacle *a* and some of these inlet tubes may be branched as indicated at *e*³, Figure 1. The receptacle *a* has also an overflow 90 pipe *f* fitted to the upper part thereof.

The lower part of the receptacle *a* is fitted 95 with an outlet *g* the open end of which is closed by a soft valve *h*, such as rubber, carried by rod *h*¹ sliding through fixed sup-

- port *i*. The rod *h*¹ carries a coiled spring *h*² in compression located between the fixed support *i* and the valve *h*, which spring closes the valve *h* against the open end of 5 the outlet *g*. The end of the rod *h*¹ carries an armature *h*³ which is attracted by the electromagnet *j* when it is desired to allow the liquid or part thereof to escape from the receptacle *a*.
- 10 An electric lamp *k* is located within the funnel *d* and is rendered incandescent at the desired times.
- 15 A card *l* and its carrier *l*¹ are indicated diagrammatically in position within the receptacle *a* by means of broken lines. The interior of the receptacle *a* may have an enlargement at *a*⁵ to allow sufficient space to ensure that the liquid shall flow over that portion of the card which has been exposed 20 to light. The remainder of the card, which may be used as a post card, is left blank.
- What I claim as my invention is:—
1. An improved developing receptacle for use in producing positive photographs, comprising a body having an open top and bottom and an opening in the side, means for closing the open bottom, a plurality of inlets for liquids at the upper end of the body, an outlet for liquids at the lower end thereof, means for closing the outlet for liquids, a transparent sheet of material closing the side opening liquid tight, and a source of light opposite to said transparent sheet, substantially as set forth. 25
2. An improved developing receptacle for use in producing positive photographs, comprising a body having an open top and bottom and an opening in one side, means for closing the open bottom, a plurality of inlets for liquids at the upper end of the body, an overflow pipe attached to the upper part of the body, an outlet for liquids at the lower end thereof, means for closing the outlet for liquids, a transparent sheet of material closing the side opening liquid tight, and a source of light opposite to said transparent sheet, substantially as set forth. 30
3. An improved developing receptacle for use in producing positive photographs, comprising a body having an open top and bottom and an opening in one side, means for closing the open bottom, a plurality of inlets for liquids at the upper end of the body, an overflow pipe attached to the upper part 35 of the body, an outlet for liquids at the lower end thereof, means for closing the outlet for liquids, a transparent sheet of material closing the side opening liquid tight, and a source of light opposite to said transparent sheet, substantially as set forth.
4. An improved developing receptacle for use in producing positive photographs, comprising a body having an open top and bottom and an opening in one side, means for closing the open bottom, a plurality of inlets for liquids at the upper end of the body, an outlet for liquids at the lower end thereof, a valve closing the said outlet, a rod by which the valve is carried, a fixed support in which the rod slides, an armature on said rod, a spring 45 in compression on said rod between the fixed support and the valve, an electromagnet to attract the said armature, a transparent sheet of material closing the side opening liquid tight, and a source of light opposite to said transparent sheet, substantially as set forth. 50
5. An improved developing receptacle for use in producing positive photographs, comprising a body having an open top and bottom and an opening in one side, means for closing the open bottom, a plurality of inlets for liquids at the upper end of the body, an outlet for liquids at the lower end thereof, means for closing the outlet for liquids, a transparent sheet of material closing the side opening liquid tight, a plate fixed to one side of the body, a socket carried by said plate, a funnel fitted within said socket and 55 a source of light located within the funnel, substantially as set forth. 60
6. An improved developing receptacle for use in producing positive photographs, comprising a body having an open top and bottom and an opening in one side, a rubber cushion for closing the open bottom of the body, a lever carrying the rubber cushion, an outlet for liquids at the lower end of the body, a plurality of inlets for liquids at the upper end of the body, an outlet for liquids at the lower end thereof, a valve closing the said outlet, a rod by which the valve is carried, a fixed support in which the rod slides, an armature on said rod, a spring 65 in compression on said rod between the fixed support and the valve, an electromagnet to attract the said armature, a transparent sheet of material closing the side opening liquid tight, and a source of light opposite to said transparent sheet, substantially as set forth. 70
- In witness whereof I have hereunto set my hand in presence of two witnesses.
- HARRY HUGH WOLFE.
